UNITED STATES PATENT OFFICE.

QUIRINO V. DISTEFANO, OF WATERBURY, CONNECTICUT.

STEERING DEVICE.

1,317,910.

Specification of Letters Patent.

Patented Oct. 7, 1919.

Original application filed December 19, 1917, Serial No. 207,951. Divided and this application filed June 6, 1918. Serial No. 238,528.

To all whom it may concern:

Be it known that I, QUIRINO V. DISTEFANO, a subject of the King of Italy, residing at Waterbury, in the county of New Haven 5 and State of Connecticut, have invented certain new and useful Improvements in Steering Devices, of which the following is a specification.

This invention relates to airships and has 10 for its object the production of a simple and efficient means for facilitating the steering of the airship.

Another object of this invention is the production of a simple and efficient means 15 for actuating the steering rudder and also efficiently supporting the same.

The present application is a divisional application from my application filed December 19th, 1917, Serial #207,951, relating to 20 airships.

Other objects and advantages of the present invention will appear throughout the following specification and claims.

In the drawings:

25 Fig. 1 is a side elevation of the air ship, certain parts thereof being broken away to show the interior construction of certain parts of the operating mechanism,

30 Fig. 2 is a section taken on line 2—2 of Fig. 1, and

Fig. 3 is a section taken on line 3—3 of Fig. 1, and

35 Fig. 4 is a detail perspective view of the guiding means for guiding the steering rudder in its movements laterally upon the body of the air ship.

By referring to the drawings, it will be seen that 1 designates the body of the machine which is provided with a rearwardly 40 extending tapering end 2 having the stabilizer 3 formed thereon for the purpose of assisting in keeping the body of the machine 1, upon an even keel. The body 1 is supported upon a plurality of rear driving wheels 4,

45 which wheels 4 are carried by a driving shaft 5 extending through a transmission casing 6 supported upon the body 1. A driving gear 7 is carried by the rear axle of the driving shaft 5 and meshes with a bevel gear 8 carried by an intermediate driving shaft 9, the shaft 9 extending longitudinally through the transmission casing 6 and carrying a beveled gear 10 upon the upper end thereof, which beveled gear 10 meshes

50 with a beveled gear 11 carried by the axle

driving shaft 12. A sprocket wheel 13 is carried by the shaft 12 and this sprocket wheel 13 is driven by a sprocket chain 14 actuated by any suitable means.

Suitable driving propellers 15, 16, 17 and 60 18 are also carried by the body 1 for the purpose of facilitating the propelling of the machine. A supporting balloon 19 is supported upon the top of the body 1, the balloon 19 being supported by suitable standards 20 carried by the pilot house 21.

65 A forward steering wheel 23 is carried by a frame 24, the frame 24 being carried by a steering rod 25, which steering rod 25 extends up into the pilot house 21 as clearly 70 illustrated in Fig. 1 of the drawings. It should be understood of course that the wheels 4 and 23 are only employed when the machine is traveling upon the surface of the ground.

75 A steering rudder 26 is extended below the body 1 upon a pivot bolt 27 and this rudder 26 is operated by means of a pinion 28, which pinion 28 meshes with a rack 29 secured to the rudder 26 for the purpose of 80 swinging the rudder 26 upon the body 1 and steering the same. This rack member 29 is provided with a pair of spaced ears 30, the ears fitting upon opposite sides of the rudder 26 for the purpose of facilitating the attachment of the rack member 29 to the rudder 26.

85 A guiding loop 31 is carried also by the upper edge of the rudder 26 and this guiding loop 31 is provided with a plurality of 90 depending spaced ears 32 fitting upon opposite sides of the rudder 26 and receiving a suitable rivet or other securing means 33 for the purpose of efficiently attaching the loop 31 to the rudder 26. This loop 31 is provided with a longitudinally extending slot 34, through which slot 34 projects one of the flanges 35 of the anchoring member 36. This anchoring member 36 is substantially U-shaped in cross section and is provided 95 with an upwardly extending knob 37 passing through the body 1 for the purpose of attaching the anchoring member 36 to the body 1. It will therefore be seen that the anchoring member 36 straddles one of the 100 parallel bars 38 of the yoke 31 and guides the rudder 26 in its lateral swinging movement.

105 From the foregoing description it will be seen that the guiding yoke 31 will con- 110

stitute an efficient means for holding the rudder 26 in proper position for permitting the pinion 28 to mesh with the rack bar 29 and in this way facilitate the 5 swinging of the rudder 26 from side to side. This pinion 28 is carried by a vertically extending shaft 39, the shaft 39 carrying a beveled gear 40 at the upper end thereof, the beveled gear 40 meshing with 10 a beveled gear 41 carried by the shaft 42, this shaft 42 also carrying a beveled gear 43 at the forward end thereof. This beveled gear 43 at the forward end of the shaft 42 meshes with a beveled gear 44 carried by 15 the rudder steering rod 45. This rod 45 extends into the cabin 21 or pilot house 21 as clearly illustrated in Fig. 1 of the drawings.

From the foregoing description it will 20 be seen that the machine described above may be readily navigated and steered from the pilot house 21, the respective steering levers projecting up through the body of the air ship to a suitable point within the 25 pilot house to permit an operator to readily have access thereto.

The foregoing description and drawings have reference to what may be considered the preferred or approved form of my 30 invention. It is to be understood that I may make such changes in construction, and arrangement, and combination of parts, materials, dimensions, etc., as may prove expedient and fall within the scope of the 35 appended claims.

Having thus fully described my invention, what I claim as new and desire to secure by Letters Patent, is:—

1. An air ship of the class described comprising a body, a rudder pivotally secured at its forward end to said body, a guiding loop carried by said rudder and projecting transversely thereof, a rack secured to the rear end of said rudder, a steering pinion meshing with said rack, means for actuating said pinion for rotating the same and shifting the rear end of said rudder laterally, and guiding means carried by said body and engaging said loop for limiting 45 the lateral swing of said rudder and constituting a support therefore for holding said rack in engagement with said pinion.

2. An air ship of the class described comprising a body, a rudder pivotally secured 50 to said body near its forward end, a guiding loop provided with a plurality of depend-

ing ears fitting over the upper edge of said rudder, said guiding loops provided with a longitudinally extending slot, a loop retaining anchor secured to the bottom of said 60 body and provided with a projecting flange extending within said slot for limiting the lateral swing of said rudder, and means for coöperating with the rear end of said rudder for swinging the same laterally upon 65 said body.

3. An air ship of the class described comprising a body, a rudder pivotally secured at its forward end to said body, a rack secured to the rear end of said rudder, a steering pinion meshing with said rack, means for actuating said pinion for rotating the same, and shifting the rear end of the rudder laterally, and guiding means for limiting the lateral swing of said rudder and 75 constituting a support therefor for holding said rack in engagement with said pinion.

4. An air ship of the class described comprising a body, a rudder pivotally secured at its forward end to said body, a slotted 80 guiding loop carried by said rudder and projecting transversely thereof, a rack secured to the rear end of said rudder, a steering pinion meshing with said rack, means for actuating said pinion for rotating the 85 same and shifting the rear end of said rudder laterally, and a loop retaining anchor secured to the bottom of said body and provided with a projecting flange extending 90 into said slot, for limiting the lateral swing 90 of said rudder and constituting a support for holding said rack in engagement with said pinion.

5. An air ship of the class described, comprising a body, a rudder pivotally secured 95 to said body at its forward end, a guiding loop secured to the upper edge of said rudder, said guiding loop provided with a longitudinally extending slot, a loop retaining anchor secured to the body of said body and provided with a projecting flange extending 100 into said slot for limiting the lateral swing of said rudder, and means for coöperating with the rudder for swinging the same laterally upon said body.

In testimony whereof I affix my signature in presence of two witnesses.

QUIRINO V. DISTEFANO.
